UNITED STATES PATENT OFFICE.

ADOLPH MUEHLEISEN AND GROVER C. MUEHLEISEN, OF SAN DIEGO, CALIFORNIA.

TENT.

Application filed May 31, 1922. Serial No. 564,723.

To all whom it may concern:

Be it known that we, ADOLPH MUEHLEISEN and GROVER C. MUEHLEISEN, citizens of the United States, residing at San Diego, in the 5 county of San Diego and State of California, have invented a certain new and useful Tent, of which the following is a specification.

Our invention relates to tents, more particularly to small camping or beach tents of the single pole type and the objects of our invention are: First, to provide a tent of this class which provides a relatively large headway at the top with a relatively low or 10 short tent; second, to provide a tent which is approximately square shaped at the top with a curved upper surface to shed water, then flares outwardly in square shape to the base, thus providing a very commodious 15 tent in accordance with its height and size; third, to provide new and novel means for supporting the top square portion of the tent; fourth, to provide a novel tent structure, and fifth, to provide a tent of this 20 class which is very simple and economical 25 of construction, durable, easy to set up and take down, efficient and which will not readily deteriorate or get out of order.

With these and other objects in view as 30 will appear hereinafter our invention consists of certain novel features of construction, combination and arrangement of parts and portions as will be hereinafter described in detail and particularly set forth in the 35 appended claims reference being had to the accompanying drawings and to the characters of reference thereon which form a part of this application in which:

Figure 1 is a top or plan view of our tent 40 set up, showing by dotted lines the position of the rigid member for supporting the square top portion of the tent. Fig. 2 is a side elevational view of the tent set up with the door flap partially open and Fig. 45 3 is a detailed perspective view showing the relation of the supporting members at the top with the corner pockets in the square portion of the top and the positioning of the ends in their supported positions.

50 Similar characters of reference refer to similar parts and portions throughout the several views of the drawings.

The tent body 1, door flap 2, pole 3, rectangular cover portion 4, diagonal curved supports 5 and 6 and pocket members 7

constitute the principal parts and portions of our tent structure.

The tent pole 3 is of the conventional type provided with a pin 3^a extending from the normally upper end thereof in the center and mounted on this pin 3^a are the two curved diagonal supports 5 and 6 by means of holes centrally in said supports, as shown in the drawings, the extended ends of the four supports forming a square, as shown best in Fig. 1 of the drawings. It will be noted that these supports are curved upwardly providing a curved top portion for the tent, as shown best in Fig. 2 of the drawings. Over these members 5 and 6 is provided a cover which is rectangular in shape and provided on the inner side of each corner with a three-cornered piece secured thereto at the edges and loose at the one side, forming a pocket into which the ends of the members 5 and 6 extend, as shown best in Fig. 3 of the drawings, the ends being rounded as shown, thus providing means for supporting the tent cover relatively to the diagonal supports 5 and 6. The body portion 1 of the tent is secured to the outer edge of the rectangular cover portion 4 and consists of strips of approximately the same width as one side of the rectangular portion 4 extending downwardly to the ground and tapering outwardly, one of which is used for a door or flap for ingress to and egress from the tent. The corners are made up of two triangular members, thus providing a flaring tent with the rectangular shaped portion 4 approximately three feet square and flaring outwardly to approximately three times the width of the top 4 in each direction, as shown best in Fig. 1 of the drawings.

Though we have shown and described a particular construction, combination and arrangement of parts and portions we do not wish to be limited to this particular construction, combination and arrangement but desire to include in the scope of our invention the construction, combination and arrangement substantially as set forth in the appended claims.

It is obvious that with this construction there is provided a tent with an approximately square shaped top with curved diagonal supports for said top, the ends of which extend into pockets in the top portion at the corners thereof and curved sufficiently

so that the center is considerably higher than the outer edge, thus providing a tent which is not very high proportionate to its capacity and provides plenty of head room 5 around the supporting center pole; that the diagonal curved supports with their ends mounted in the pockets at the corners provide a rigid support for the tent top and also providing a sufficiently curved top to 10 shed rain; that the pockets 7 are so shaped and positioned that the ends of the members 5 and 6 are easily placed therein.

Having thus described our invention what we claim as new and desire to secure by 15 Letters Patent is:

1. A tent of the class described, including a center pole with a pin in the upper end thereof, a pair of diagonally positioned curved supports provided with central holes 20 mounted on said central pole, and a square shaped cover provided with pockets at each corner into which the extended ends of said curved supports extend for rigidly supporting said cover supports and holding them 25 in their certain relative positions to each other, and a flaring tent body secured to the outer edge of said square shaped cover and extending outwardly and downwardly to the ground.

30 2. A tent of the class described, including a rectangularly shaped top, curved

means for supporting said rectangular shaped top so that the center is slightly higher than the outer edge and a central pole engaging and supporting the central 35 portion of said means.

3. A tent of the class described, including a central pole provided with a pin in the upper end in the center thereof, a pair of curved supporting members with holes in 40 their centers mounted over said pin, a square shaped cover member provided with pockets in each corner adapted to engage the extended ends of said supporting members whereby said square shaped cover member and said supports are held in certain 45 relative positions to each other, whereby said supports are diagonal to said square shaped cover, and a tent body secured to the outer edge of said square shaped cover.

50 4. A tent of the class described, including a central pole, a rectangularly shaped, curved and reinforced top provided with holes in the center with which said pole engages and a tent body secured to the outer edge of said rectangularly shaped top and supported at the lower corners.

In testimony whereof, we have hereunto set our hands at San Diego, California, this 23d day of May, 1922.

ADOLPH MUEHLEISEN.
GROVER C. MUEHLEISEN.
